UNITED STATES PATENT OFFICE.

JACOB OSCAR ZIEGLER, OF BOSTON, MASSACHUSETTS, ASSIGNOR TO
THE ZIEGLER ELECTRIC COMPANY, OF SAME PLACE.

GAS-BURNER.

SPECIFICATION forming part of Letters Patent No. 550,149, dated November 19, 1895.

Application filed January 26, 1895. Serial No. 536,384. (No model.)

To all whom it may concern:

Be it known that I, JACOB OSCAR ZIEGLER, of Boston, county of Suffolk, State of Massachusetts, have invented an Improvement in 5 Gas-Burners, of which the following description, in connection with the accompanying drawings, is a specification, like letters on the drawings representing like parts.

This invention relates to gas-burners, particularly to that type of burner known as a "Bunsen," the object of the invention being to provide novel means for simultaneously varying the air and gas inlets for the regulation of the flame and preferably to provide a 15 differential variation of said inlets, whereby the ratio between the inlets is maintained substantially constant whatever be the degree of opening.

In the drawings, Figure 1 is a side elevation of one embodiment of my invention; Fig. 2, a vertical section through the same; Fig. 3, a horizontal section on the dotted line $x-x$, Fig. 2; Fig. 4, a horizontal section on the dotted line $x'-x'$, Fig. 2; and Fig. 5 a sectional detail, on an enlarged scale, of the parts immediately surrounding the burner.

In the embodiment of my invention illustrated in the drawings, A is a suitable base provided with an upwardly-extended internally-threaded nipple a , at one side of which is arranged the gas-inlet a' , preferably through a suitable pipe a^2 , as shown.

The base A at the bottom of the nipple a is perforated and the perforation threaded to receive the screw b , having its shank b' projected vertically within the nipple and its preferably tapered end b^2 constituting one member of the valve for regulating the supply of gas. Co-operating with the valve member b^2 is a thimble c , externally threaded and screwed into the nipple, as shown, and having its top c' constituting the second gas-valve member, made conical to co-operate with the member b^2 and perforated at c^3 for the exit of the gas. The thimble c (see Fig. 5) has secured to its end the tube d , from the end of which the gas flame is projected when in use, the said tube d being rotated by or with the said thimble and, as herein shown, having 45 adjacent the conical end of the said thimble

two oppositely-arranged air-inlet openings d' , to be referred to.

Secured to the base at one side of the nipple a I have shown a post e , upon which is loosely journaled an intermediate connection f , (shown as comprising two connected gears f' and f^2 ,) the gear f' meshing with a gear c^3 , fast on and rotatable with the thimble c and its attached tube d , the gear f^2 being in mesh with the gear h , fast on the lower end of a valve-sleeve h' , loosely surrounding the tube d and provided with inlet-openings h^2 , corresponding in size and location with the air-inlets d' in the said tube. The gears c^3 and h , as herein shown, are provided with the same number 55 of teeth, while the gears f' and f^2 of the intermediate connection, as herein shown, are provided with a different number of teeth, the gear f^2 in the present instance having one less tooth than the gear f' , forming thereby 60 differential gearing to operate the gas and air inlets. An annular and milled disk i , rotatable with the thimble c and tube d , enters the space between the gears f' and f^2 of the intermediate connection f^3 , said disk i thereby 65 supporting the said intermediate connection 70 upon its post e and forming an actuator having a vertical movement with the thimble and tube in the operation of the burner to be described.

In the normal condition of the apparatus the thimble c is in its lowermost position, with its conical end fitting tightly upon the conical end of the valve-screw b , the inlets d' in the tube d being nearly or quite covered by the surrounding sleeve h' . To start the burner, the disk i is rotated in the direction of the arrow 25, Figs. 3 and 4, and by means of the differential gearing the gear f' will be rotated by the gear c^3 in the direction of the 75 arrow, Fig. 4, to cause its thimble to be more or less unscrewed from the nipple a to lift the valve member c' from the co-operating member b^2 to admit gas through the orifice c^3 into the tube d , the gear f^2 at the same time 80 rotating its meshing gear h and the sleeve h' also in the same direction, but at a slightly different speed, and thereby causing a relative movement of the said sleeve and tube d to 85 slightly open or increase the opening of the 90 95 100

air-inlets d' to admit air therethrough to mix with the gas to support the combustion. From this it will be clear that by rotation of the actuator or disk i in one or the other direction the valve member c' will be moved toward or from its co-operating member b^2 to regulate the supply of gas, and at the same time the gear f^2 , having a different number of teeth from the gear f' , imparts to the sleeve h' a faster or slower rotation, as the case may be, to thereby open or close the air-inlets d' in the sides of the tube d^2 in a fixed ratio to the gas-inlet. The sleeve h' constitutes a valve to regulate the air-inlets, and the thimble c constitutes in effect the valve to regulate the gas-inlet, both having a common actuator. In the present device, for instance, inasmuch as the opening of the air-inlets is greater than the opening of the gas-orifice, the movement to open or close the air-inlets must be more rapid than the movement to open or close the gas-inlet in order to preserve the constant ratio between their areas.

While I prefer to incorporate my invention in a device similar to that herein shown and described, yet my said invention is not necessarily limited to such construction.

I claim—

1. In a burner of the class described, a base having a gas inlet, a valve seat, and a valve therefor having a relative movement to open and close said gas inlet, a tube leading from the said valve through which the gas is projected, one or more air inlet openings in the side of the said tube, a valve controlling the same, and intermediate gearing to cause simulta-

neous movement of the said gas and air valves, substantially as described.

2. A gas burner comprising a vertically movable threaded gas valve and its attached tube, provided with lateral air inlets, a valve shield encircling the said tube, gears connected respectively to the said tube and shield, an intermediate connection in mesh with both of said gears, the gears for moving the said tube and shield having a different number of teeth whereby simultaneous differential rotation of the said tube and shield is obtained, substantially as described.

3. A base, an internally threaded nipple thereon, a valve member standing vertically within the said nipple, a thimble screwed into the said nipple and co-operating with the said screw to regulate the supply of gas, a tube on and rotatable with the said thimble and having lateral air inlets, a regulating shield encircling the said tube to open and close the said air inlets, gears on and to move said thimble and shield, a post standing at one side of said nipple, and an actuator loosely rotatable thereon and comprising two gears meshing respectively with the said gears on the thimble and shield, said actuator rising and falling with the said thimble during rotation of the latter, substantially as described.

In witness whereof I have signed my name to this specification in the presence of two subscribing witnesses.

JACOB OSCAR ZIEGLER.
